FRANK BUCHANAN, OF SYRACUSE, NEW YORK.

CONSUMING ELECTRODE FOR LUMINOUS-ARC ELECTRIC LAMPS.

1,193,866.

Specification of Letters Patent. Patented Aug. 8, 1916.

Application filed February 24, 1912. Serial No. 678,577.

To all whom it may concern:

Be it known that I, FRANK BUCHANAN, of Syracuse, in the county of Onondaga and State of New York, have invented a new and useful Consuming Electrode for Luminous-Arc Electric Lamps, of which the following is a specification.

This invention relates to electric arc lamps and particularly to a luminous arc electrode by which the arc is confined to very little travel laterally from the focal axis of the light focusing means as a lens or a reflector; and it consists in the novel combinations and constructions hereinafter set forth and claimed.

In describing this invention reference is had to the accompanying drawing in which like characters designate corresponding parts in all the views.

20 Figure 1 is a sectional view of a head-light embodying my invention. Fig. 2 is an elevation of the opposing end portions of the consuming and non-consuming electrodes of a luminous arc electric lamp embodying my invention. Fig. 3 is a cross sectional view through the consuming electrode looking upwardly, in Fig. 2, showing the lower electrode plotted on the end face of the upper electrode. Fig. 4 illustrates the possible angle of refraction or reflection of the rays of light out of parallelism with the focal axis of the lens of an electric arc lamp, due to the travel of the arc when the ordinary cylindrical luminous arc electrodes are used. Fig. 5 illustrates the possible angle of refraction or reflection due to the travel of the arc when my electrode is used.

1 designates the non-consuming electrode; 2 the consuming electrode, and 3 one form of light focusing means as the lens of a search or head light, the focal axis of the lens being shown by the line "A—A". 3^a designates another form of light focusing means, as a reflector. The electrodes are usually arranged on opposite sides of, that is in axial alignment above and below, the focal axis of the lens near the focusing point thereof so that the luminous flame or arc will be located as near as possible to such focusing point.

The non-consuming electrode, so called because it consumes slowly, is usually the upper and positive electrode and is a cylin-

drical copper rod of as large diameter as practical to have enough body to cool with sufficient rapidity to avoid oxidizing or scaling.

The consuming electrode 2 is preferably the lower or negative electrode and is usually composed of a tubular metallic shell for conducting the electric current and a material within the shell which acts to steady the arc and also to render the same luminous, as will be understood by those skilled in the art, the luminosity and the steadiness of the arc being largely dependent upon the proportion of the metal of the outer shell to such material. This material may contain metallic oxides, as for example the oxides of titanium, iron and chromium or may be the composition described in my pending application Sr. No. 639,019, filed June 19, 1911.

In electric arc lamps having both electrodes standing at an angle to the focal axis of the light focusing means, the electrodes have heretofore been formed cylindrical and thus the arc will have a travel laterally a maximum distance from the focal axis of the light focusing means, and to confine the travel of the arc to a minimum distance, I form one of the electrodes oblong in general outline in cross section and preferably I form the consuming electrode oblong in cross section.

In consuming electrodes the shell has heretofore been formed cylindrical as indicated at 4, Fig. 4, and hence the arc may travel from the focal axis designated "A—A" laterally in either direction to the points 5, that is a distance equal to the radius of the cylinder. Thus the rays of light will have a possible divergence out of parallelism with the focal axis of the light focusing means an amount indicated by the angle λ , δ , ϵ , it being understood that in electric lamps having lenses as head lights, it is desirable to project the light rays straight ahead in parallelism with the focal axis of the lens, to form a shaft of light, and that any lateral divergence of the rays out of parallelism with such axis throws the light laterally and thus the shaft is projected laterally to the right or left, so that in case of head lights on railway cars, the shaft of light is not thrown on the track but on one side or the other of the track.

To confine the travel of the arc to a minimum distance laterally relatively to the focal axis of the light focusing means, I form the consuming electrode oblong in general outline in cross section, and arrange the electrode with its greatest cross sectional dimension extending in the direction of said focal axis, as seen in Fig. 5, the shell 6 of the consuming electrode being flattened from the 10 cylindrical form, a maximum degree without substantially varying the proportion of the metal to the material within the shell at the arc end of the electrode from the proportion of the metal to such material in a cylindrical electrode operating under the same conditions and of the same cross sectional area.

In my electrode the travel of the arc laterally is a distance equal to the shortest radius of the electrode, that is, from the focal 20 axis "A—A" to the points 7, and the divergence of the rays of light out of parallelism with the focal axis of the lens or reflector is confined to a minimum angle, indicated by the angle A, b, d. Thus by forming the electrode oblong in cross section an electrode is produced having the same proportion of conducting metal and metallic oxide as in a cylindrical electrode of practically the same cross sectional area.

30 By the term "oblong in general outline in cross section" applicant means any form having long and short diameters arranged at an angle to each other.

What I claim is:

35 1. In an arc lamp equipped with a fo-

cusing element, two electrodes arranged in superimposed relation, and with the arc ends thereof on opposite sides of the focal axis of said element, said electrodes being of dissimilar cross-sectional area, and the electrode of smaller area being of greater dimensions in the direction of one transverse axis than in the direction of its other transverse axis, said longer axis being disposed in the direction of said focal axis of the focusing element, substantially as and for the purpose described.

2. In an arc lamp the combination with a focusing element, of a metallic positive electrode and a slow consuming luminous negative electrode arranged beneath the metallic electrode, and on the opposite side of the focal axis of said focusing element, said metallic electrode being larger in cross-sectional area than the negative, and the latter being 50 substantially oblong in cross-section and arranged with its longer transverse axis substantially parallel to the focusing axis of said focusing element, substantially as and for the purpose specified.

In testimony whereof, I have hereunto signed my name in the presence of two attesting witnesses, at Syracuse, in the county of Onondaga, in the State of New York, this 20th day of February 1912.

FRANK BUCHANAN.
